MOSES H. FREEMAN, OF SOMERVILLE, MASSACHUSETTS.

Letters Patent No. 64,656, dated May 14, 1867.

PIPE-WRENCH.

The Schedule referred to in these Letters Patent and making part of the same.

TO ALL PERSONS TO WHOM THESE PRESENTS SHALL COME:

Be it known that I, MOSES H. FREEMAN, of Somerville, in the county of Middlesex, and State of Massachusetts, have invented an improved Pipe-Wrench, and do hereby declare the same to be fully described in the following specification, and represented in the accompanying drawings, of which—

Figure 1 is a side elevation; and

Figure 2 a vertical section of it.

Figure 3 is a transverse section of it, taken through its clasp.

In the said drawings, A denotes a stationary jaw projecting from a bar, B, at a right angle, or thereabouts, therewith, the said bar being provided with a handle, G, and also with a series, C, of notches made in that edge of it from which the jaw projects, and with respect to such jaw, as shown in fig. 2. A clasp, D, encompasses the bar B, and projects back from a lever, F, carrying a movable jaw, E. The said lever F, whose fulcrum is a tooth, a , which extends from it into one of the notches of the series C, is formed and arranged with the clasp as represented in fig. 2. A spring, H, is placed within the clasp D, fastened at its middle thereto, and is arranged so that near its ends it may bear against the bar B, the same being as represented in fig. 2. The lever F, fixed to the slide D, will be moved by it whenever such slide is moved either laterally or longitudinally with respect to the bar B. The slide should have so much lateral play on the bar B as to enable a person, by moving the slide on and transversely of the bar, to move the lever in a manner to disengage its tooth, a from the series of notches, in order that the slide, with the jaw F, may be moved either nearer to or further from the stationary jaw A. The spring H serves to draw the slide back so as to bring the tooth into the notch intended to receive it. It also serves to close the jaw E upon a pipe. By pressing on the tail of the lever F, so as to force it toward the bar B, the jaw E will be moved so as to make a greater angle with the face of the jaw A, such being to open the jaws so as to enable them to receive a pipe, after the movable one may have been adjusted to its proper distance from the other, for holding the pipe against it. In this wrench the adjustment of the movable jaw can be very easily or quickly effected, as will be readily observed by most if not all persons skilled in mechanism.

What I claim in it is the combination as well as the arrangement of the clasp D and spring H, the tooth A, the series C of notches, the jaws E A, and the bar B.

I also claim the combination as well as the arrangement of the lever F with the clasp D, the spring H, the tooth a , the series C of notches, the jaws E A, and the bar B, such bar being provided with a handle, and the whole being constructed so as to operate substantially as hereinbefore explained.

MOSES H. FREEMAN.
